CLOTH SHRINKING MACHINE

Burt J. Shaw, Rochester, N. Y., assignor to
 Fashion Park Manufacturing Corporation,
 Rochester, N. Y., a corporation of New York

Application June 20, 1934, Serial No. 731,418

9 Claims. (Cl. 26—46)

My invention relates to an improvement in a cloth shrinking machine and its novelty consists in the adaptation and combination of parts and in the process of carrying out said cloth shrinking as will be more fully hereinafter pointed out.

This application is a continuation of my application Serial No. 697,761, filed November 13, 1933, Patent No. 1,988,519 of January 22, 1935.

The cloth shrinking machines now on the market adapted for the shrinking of woolen cloths such as used in men's clothing, all require a pulling of the cloth through the various steaming, water bath and removal of the surplus water in order to effect a proper shrinking of the cloth and thereby stretch the cloth lengthwise and narrow the cloth in width because of said pulling.

This shrinking of the cloth is absolutely essential in order to have the cloth in proper condition for cutting and making up into clothing, as otherwise the goods will shrink after the clothing is made up and thereby cause a suit which was a perfect fit when made to become too short and too small around to fit the person for whom the clothes were made.

In carrying out the shrinking operation on the devices now on the market or on any of those represented by prior patents also, causes a distortion of the cloth making it too long and too narrow and also too thick so that when made up into a suit it causes the suit to become readily baggy and also loses a substantial amount of the cloth because of the narrowing of the fabric and the thickening of the same.

My process and machine for carrying out the same overcome this most serious problem and insure an even shrinking of the entire fabric treated without any longitudinal or lateral distortion and insuring a fabric which will make up into garments that will not shrink or become baggy because of the undue thickness of the fabric through distortion.

Referring to the drawings, Figure 1 is a side elevation of my complete device with a portion of the bath vat broken away for convenience in illustration and showing the complete surplus water removal and distributor circulation system.

Figure 2 is a top plan view of Figure 1 with two portions broken away in order to show the construction beneath.

In the drawings, on the base or floor 3 is rigidly mounted by means of bolts 4 in the usual way, a pair of end frame members 5 of suitable cast iron or steel which are of a V type and are designed and flanged to accommodate cross members 6 of suitable thick wood forming the sides of a V type vat 7, and the ends 5 are rigidly secured together by means of iron rods 8 whereby the wooden cross members 6 may be securely clamped tightly to each end 5. On the

inside of each of the ends 5 is rigidly secured a pair of angle irons 9 forming between each of said pairs of angle irons 9 a vertical slot 10 in which the ends of a shaft 11 of a riding roller 12 is adapted to slide as the roller rides up and down. Rigidly secured to each of the upper edges of the two end frames 5 in the usual manner by means of bolts 13 are brackets 14 adapted to suspend shafts 15 and 16, on the usual roller bearings 15a and 16a respectively, of driven rollers 17 and 18 having respectively flanges 19 and 20. To the outer end of the shaft 15 is rigidly secured in the usual way a pulley 21 by means of which power from an outside source (not shown) is transmitted to said shaft 15 and to roller 17 thereon. A pulley 22 tapered toward the roller 17 is also mounted in the usual way on said shaft 15 and a pulley 23 tapered away from roller 18 is also mounted in the usual way on shaft 16 and a belt 24 is mounted over said tapered pulleys 22 and 23 running through guide 25, of usual construction mounted to the side of the frame 5, whereby the belt 24 can be guided to run on the small tapered portion of tapered pulley 22 and on the larger portion of tapered pulley 23 so as to insure the shaft 16 turning a little more rapidly than 15 whereby the roller 18 will rotate more rapidly than roller 17. This will insure the cloth 86 being fed to the water vat 7 coming in at a slightly more rapid rate than it leaves the vat so as to prevent any possible pull on said cloth 86 due to shrinkage as it passes through said vat 7.

At the left hand end of Figure 1, which is the starting point of my device, is rigidly secured to each of the ends 5 in the usual way at 26, a pair of brackets 27 on which is rigidly secured in the usual way at 28 a platform 29. On the platform 29 is rigidly mounted a steam box 30 of usual construction which is fed by an outside source of steam through pipe 31 and which is controlled by hand valve 32 in the usual manner.

To each of the end members 5 is rigidly secured at 33 in the usual manner end frame members 34 which are rigidly secured at 35 to the base 3. These end frames 34 are rigidly secured together at the properly spaced distances by means of rods 36. At the right hand upper end of Figure 1, which is the finishing end of my machine, is rigidly secured at 37 to each of the frame members 34 a pair of brackets 38 in which are supported usual roller bearings 39 and in said bearings 39 is mounted shaft 40 of an idling roller 41. Immediately below said roller 41 is rigidly secured at 37 to each of the frame members 34 a pair of brackets 38 on which is rigidly supported a drier 39 in the usual manner having a slot or opening 40 for practically its entire length.

Rigidly secured to each of the frames 34 in 60

the usual manner at 41 is a box 42 which is held in rigid position on said frames 34 at each end by means of plates 43 which are fastened over the ends of said box 42 by means of the usual 5 bolts 44. Said box 42 has a foraminous cover 42a which may be omitted if desired.

In said box 42 is a pipe 45 running the entire length of said box and having a narrow slot on the upper face of said pipe for substantially the 10 entire length of the same immediately under said foraminous cover 42a in said box 42. Said pipe 45 extends down from each end of said box 42 to a T 46 in the middle underneath said end frames 34 and from said T 46 said pipe 45 continues 15 in a single pipe to T 47 where pipe 48 runs up to vacuum chamber 49 of usual construction and said pipe 48 continues on into electrically operated automatic vacuum control 50 of usual construction now in general use, 20 adapted to automatically maintain a fixed vacuum slightly above that required for the heavy cloth and having electrical connections 51 to a source of power not shown. This may for example be set for a maximum vacuum of 10 25 inches for the heavy cloth. When that maximum is reached a pump 53 will stop. More air will be pulled through the light weight fabrics in a given time and this lowers the vacuum in the system as required. From T 47 pipe 45 continues 30 through strainer 52 of usual well known construction and thence into said pump 53 of well known construction and from pump 53 continues on in pipe 45 into a separating tank 55 of usual well known construction, said tank having 35 the usual air exhaust 56 at its upper end. The pipe 45 then continues from the bottom of this separating tank 55 to mixing tank 57 which has on its side a water inlet 58 controlled by valve 59 and said pipe 45 continues from the bottom 40 of said mixing tank 57 to the T 60 from which there is a drain pipe 61 controlled by valve 62, draining off to a waste (not shown) and the pipe 45 continues from said T 60 through one of the ends 5 of the vat 7 where it passes through 45 a float valve 63 of usual construction located inside of vat 7 and terminates in a water feed 66 which maintains the water level in said vat 7 by the control of the said float valve 63 in the usual well known manner.

50 It is thus seen that the water feed and supply is renewed and largely maintained by the surplus water taken through the vacuum or surplus water remover system and the threads or pieces of wool which may be taken in said water 55 removed from the cloth treated will be strained out in strainer 52 before it enters the pump 53 and the normal atmospheric pressure is restored to said water in the separating tank 55 before it is returned to the mixing tank or source of 60 water supply 57.

A perforated metal endless apron or conveyor 72, preferably made of a wire mesh, is adapted to pass over rollers 17 and 71 and a guide roller 73, having shaft 74 mounted in the usual roller bearings which in turn are mounted in brackets 65 75 secured in the usual well known manner to each of the frames 34. A tension roller 76 having a shaft 77 is mounted in the usual roller bearings in the frames 78 which through the usual gear and threaded shaft are moved back and forth by means of the turning of the hand wheel 79 on the frame 80 which is rigidly secured to the frames 34. This tension roller 76 is adapted to place more or less tension on the 70 75 endless apron or conveyor 72 as the tension

roller 76 is thereby moved back and forth in alignment with the travel of the endless conveyor 72 passing thereover.

A guide roller 81 having a shaft 82 mounted in the usual way on roller bearings in frames 83 is pivoted at the far end as shown in Figure 1 and adapted to be moved back and forth at the near end in said Figure 1, changing the direction of the endless conveyor 52 as it passes on to rollers 17 from roller 81. This is accomplished through the usual gear and threaded shaft construction by means of hand wheel 84 on the base frame 85 rigidly secured to the frames 34 in the usual manner. Through this pivotal movement of the said guide roller 81 to the desired position the line of movement of the endless conveyor 72 passing thereover is thrown into and can be maintained in perfect alignment by said pivotal adjustments as it passes on to the driven roller 17. 15 20

In operating my device, a complete piece of goods or fabric 86 as it comes from the mill will be placed on the platform 29 and fed through steam box 30 in which there is the proper amount of steam for the steam treatment so 25 that the fabric will be thoroughly steam treated. The said fabric 86 will then be passed over the driven roller 18 down into the vat 7 which is filled with water and maintained so at the proper level, and thence under the riding roller 12 30 which rides on said fabric 86 but does not throw any tension thereon as it rides up readily in slots 10 but insures a complete submersion of the cloth in order to take up the necessary water for saturation and effect shrinking. The fabric 35 then travels up over the driven roller 17 which travels at a slightly less speed than roller 18 so that even after shrinking the fabric 86 is not put under any tension thereby. The fabric 86 travels then on the endless conveyor 72 over 40 the vacuum slot 45 whereby the surplus water is removed and the remaining water evenly distributed throughout the fabric insuring a uniform moisture in the fabric 86 as it leaves said vacuum slot 45. The fabric 86 then passes on 45 over roller 71 on said conveyor 72 and through the slot 40 into the drier 39.

The necessary vacuum will be maintained at the vacuum slot 45 by means of the operation of the automatic vacuum control 50 as previously described so that variations in thickness of cloth or in amount of moisture in the cloth at the vacuum slot 45 will not effect the vacuum necessary to insure the removal of the surplus water and distribution of the remaining water 55 throughout the fabric treated.

Particular attention is called to the operation of my device which is so arranged and carries out the process so that the fabric being shrunk or treated receives at all times a uniform steam treatment, a sufficient water bath and uniform removal of surplus moisture distributing evenly throughout the fabric the moisture remaining therein, all of which is accomplished without any dragging, pulling or tension on the fabric 60 treated throughout the entire operation. This uniform and complete shrinking operation insures for the first time in this art, fabric which is not only completely and uniformly shrunk but which is so shrunk without any distortion, 65 either as to length or width of the fabric, thereby insuring a perfect fabric for manufacture into articles of clothing without the possibility of subsequent shrinking or bagging. This process and apparatus also insures the fabric re- 70 75 75

maining of even thickness throughout so that there is no loss in the measure of the fabric for cutting purposes either in width or in length.

It will be apparent that many variations may 5 be made in the particular structure of my device without departing from the spirit and intent of the same, and the claims have been carefully prepared to and are intended to cover any and all of such variations.

10 I claim:

1. In a cloth shrinking machine a steam box, a water bath, means for feeding the cloth to be shrunk through said steam box and thence through said water bath comprising a pair of driven rollers mounted thereon at each end and connected so that the first rotates slightly more rapidly than the second and a riding roller in said bath between said driven rollers, means for feeding said cloth from said bath over a surplus water remover and distributor into a drier comprising an endless perforated conveyor passing over a vacuum slot, both of said feeding means operating without stretching said cloth and automatic means for regulating the suction 20 of said surplus water remover and distributor.

2. In a cloth shrinking machine a steam box, a water bath, means for conveying the cloth to be shrunk to and through said steam treating means, thence to and through said water bath, thence to and over a surplus water remover and distributor and avoiding any pulling directly on said cloth during said entire travel comprising a pair of driving rollers mounted at the upper edge of each end of said water bath in which is mounted a riding roller and said driving rollers connected so that the first rotates slightly more rapidly than the second and an endless perforated conveyor running over the second of said driven rollers and an idler roller at the finishing end of said machine and automatic means for regulating the suction of said surplus water remover and distributor.

3. In a cloth shrinking machine a steam box, a water bath, means for feeding the cloth to be shrunk through said steam box and thence through said water bath comprising a pair of driven rollers at each end of said bath connected so that the first rotates more rapidly than the second and a riding roller in said bath between, means for feeding said cloth from said bath over a surplus water remover and distributor into a drier consisting of an endless perforated conveyor passing over a vacuum slot, both of said feeding means operating without stretching said cloth, means for regulating the tension of said endless perforated conveyor and automatic means for regulating the suction of said surplus water remover and distributor.

4. In a cloth shrinking machine a steam box, a water bath, means for conveying the cloth to be shrunk to and through said steam treating means, thence to and over a surplus water remover and distributor and avoiding any pulling directly on said cloth during said entire travel comprising a pair of driving rollers connected so that the first rotates more rapidly than the second and mounted at each end of the upper edge of said bath in which is mounted a riding roller, an endless perforated conveyor running over

the second of said driven rollers and an idler roller at the finishing end of said machine and means for regulating the tension of said endless perforated conveyor and automatic means for regulating the suction of said surplus water remover and distributor. 5

5. In a cloth shrinking machine a steam box, a water bath, means for feeding the cloth to be shrunk through said steam box and thence over a driven roller and under a riding roller in said water bath, thence over a second driven roller onto an endless perforated conveyor, said driven rollers being connected so that the first rotates more rapidly than the second, thence on said conveyor over a surplus water remover and distributor and finally over an idler roller to a drier and automatic means for regulating the suction of said surplus water remover and distributor comprising an automatic vacuum control and pump. 10 15 20

6. In a cloth shrinking machine a steam box, a water bath, means for feeding the cloth to be shrunk through said steam box and thence over a driven roller and under a riding roller in said water bath, thence over a second driven roller onto an endless perforated conveyor, said first driven roller rotating more rapidly than the second, thence on said conveyor over a surplus water remover and distributor and finally over an idler roller to a drier and automatic means 25 30 35 for regulating the suction of said surplus water remover and distributor, means for straining said water before passing through a pump controlled by the established vacuum and restoring said water to a normal pressure and returning same to the source of water supply for recycling.

7. In a cloth shrinking machine a steam box, a water bath, means for feeding the cloth to be shrunk through said steam box and thence through said water bath comprising a pair of driven rollers mounted thereon at each end and connected so that the first rotates slightly more rapidly than the second and a riding roller in said bath between said driven rollers and means for feeding said cloth from said bath into a drier, both of said feeding means operating without stretching said cloth. 40 45

8. In a cloth shrinking machine a steam box, a water bath, means for feeding the cloth to be shrunk through said steam box and thence through said water bath comprising a pair of driven rollers mounted thereon at each end and connected so that the first rotates slightly more rapidly than the second and a riding roller in said bath between said driven rollers and means for feeding said cloth from said bath into a drier comprising an endless perforated conveyor. 50 55

9. In a cloth shrinking machine a steam box, a water bath, means for feeding the cloth to be shrunk through said steam box and thence through said water bath comprising a pair of driven rollers mounted thereon at each end and connected so that the first rotates slightly more rapidly than the second and a riding roller in said bath between said driven rollers and means for feeding said cloth from said bath into a drier comprising an endless perforated conveyor and means for regulating both the direction and the tension of said endless perforated conveyor. 60 65 70
